UNITED STATES PATENT OFFICE.

WILLIAM STARLING BURGESS, OF NORTH CHEVY CHASE, MARYLAND, ASSIGNOR TO
CURTISS AEROPLANE AND MOTOR CORPORATION, A CORPORATION OF NEW YORK.

DESIGN FOR A HYDROAEROPLANE-PONTOON.

53,882.

Specification for Design.

Patented Oct. 7, 1919.

Application filed November 9, 1917. Serial No. 201,181. Term of patent 7 years.

To all whom it may concern:

Be it known that I, WILLIAM STARLING BURGESS, a citizen of the United States, residing at North Chevy Chase, county of Montgomery, State of Maryland, have invented a new, original, and ornamental Design for a Hydroaeroplane-Pontoon, of which the following is a specification, reference being had to the accompanying drawings, forming a part thereof.

Figure 1 is a top plan view of the pontoon, and

Fig. 2 is a side elevation.

I claim:

The ornamental design for a hydroaeroplane pontoon, substantially as shown.

WM. STARLING BURGESS.

Witness:

CHAS. E. BAUCH.
